United States Patent Office.

WALTER G. BROWNSON, OF WELLSVILLE, OHIO.

Letters Patent No. 78,578, dated June 2, 1868.

IMPROVEMENT IN TELEGRAPHIC REPEATERS.

The Schedule referred to in these Letters Patent and making part of the same.

TO ALL WHOM IT MAY CONCERN:

Be it known that I, WALTER G. BROWNSON, of Wellsville, in the county of Columbiana, and State of Ohio, have invented a new and improved Telegraphic Apparatus, and method of operating the same; and I do hereby declare the following to be a full and exact description thereof, reference being had to the accompanying drawings, forming a part of this specification, in which—

Figure 1 is an elevation, partially in section, of my improved telegraphic key or circuit-breaker.

Figure 2 a plan, and

Figure 3 a central longitudinal section of my improved receiving-instrument.

Figure 4 a plan, and

Figure 5 a central longitudinal section of my improved repeater.

Figures 6 and 7, diagrams, illustrating the effect and operation of my invention.

Similar letters indicate like parts in all of the figures.

The nature of my invention consists in so constructing and combining the various instruments in an electro-magnetic telegraph system for the reception and transmission of telegraphic signals, as that—

First, the main circuit shall be kept constantly closed by the key or circuit-breaker when at rest.

Second, with the main circuit closed by the key when at rest, the usual movements of said key in writing shall, by opening instead of closing the main circuit, produce, announce, and repeat, in the usual manner, and without reversal, the customary signals upon the sounders, registers, and repeaters of the apparatus.

Third, the local battery-circuits of the apparatus shall be closed by the opening of the main circuit, and opened by the closing thereof.

It relates also to the form and construction of the key or circuit-breaker; to the position and arrangement of the insulated and connecting points, in combination with the armature-levers of the receiving-sounder, registering, relay, and repeating-magnets, and to the connection of local circuit-wires therewith; to the general construction of the repeating-instruments, and to the combination of main and local circuit-wires therewith; and, specially, to improved adjusting-posts in the repeating-instruments, and an improved switch for cutting out the local and main circuit therefrom.

In the accompanying drawings, fig. 1, illustrating my improved key, A represents its lever, pivoted in the usual manner between pillars *b b*, upon a base-plate, B, provided with screws and nuts *d*, to secure it to the table C. The shorter end *c* is fitted with a screw-connecting point, tipped with platina *e*, and which rests upon a platina point projecting from an insulated anvil, *f*. The constant contact of the platina tip *e* with the platina point of the anvil *f*, when the key is at rest, is secured by means of a spring, *g*, interposed between the longer arm *c'* of the lever and the base-plate B. This spring serves a double purpose by forming a conductor between the lever and its base-plate, for the passage of the electric current. The key is provided with the usual finger-button D, and a rest, *h*, projecting from the base-plate.

The wires, 1, 2, forming the main circuit, are connected and secured, the one to the insulated anvil *f*, the other to the base-plate B of the key.

When the key is at rest, (as illustrated in fig. 1, and diagram, fig. 6,) the spring *g*, maintaining by its force a contact of the lever with the anvil through the platina connecting-points at *e* and *f*, closes the circuit through the wires 1 and 2, the lever A, its spring, *g*, and base-plate B being made to form a part of said circuit. Pressure applied to the button D, lifting the point *e* from the anvil *f*, will break and open the circuit at the operator's pleasure.

Fig. 3 of the drawings illustrates my improvement in construction of the receiving and sounder-instruments to adapt them to the purposes of my invention. It consists in so disposing the ordinary insulated and connecting-points *i* and *k*, limiting the movements of the armature-lever E of the instrument, as that the tension of the spring *l* upon said lever, when it is not overcome by the attraction of the magnet, excited by an electrical current from the main circuit, shall bring said lever in contact with the connecting-point *i*, to close the local

circuit through the same, instead of with the insulated point *k* opening or breaking the circuit, so that a break in the main circuit will instantly close the local circuit by the tension of the spring *l*, as illustrated in the drawings, figs. 2 and 3, and the diagram, fig. 7.

My improved repeating-instrument is illustrated in figs. 4 and 5 of the drawings. The magnets *F* and armature-lever *G* are arranged and disposed in the usual manner, the lever *G* being pivoted at *m* between suitable posts *H H'*, with its longer arm projecting over the magnets *F* to a suitable stop, *I*, and its shorter arm extending back to a connecting-post, *K*, provided with a platina point coming into contact with a similar point on said shorter arm.

A tension-spring, *O*, attached to an arm extending at right angles to the pivot-axis of the lever, serves, by its tension, to keep the shorter arm of the lever constantly in contact with the post *K*, when this tension is not overcome by the superior attractive power of the magnets *F*, excited by the electrical current of the local circuit.

Between the pivot-axis of the lever and the magnets, and at right angles to its length, is placed a connecting-spring plate, *p*, supported at one end by the post *L*, and coming in contact at its free end, when the lever is at rest, with a platina point upon a screw, *r*, projecting vertically through an arm, *s*, extending from a post, *M*. The peculiar construction of the post *M*, with its projecting arm, *s*, and vertical platina-pointed screw, *r*, permits a nice adjustment of the connecting-spring *p* with reference to the insulated point of a screw, *t*, projecting through the lever to strike said spring, (when the lever is borne down by the attraction of its magnet,) and break its contact with the screw *r*.

The lever *G* and rear post *K* (say of east repeater) are respectively connected with the wires of a local circuit connected with the relay of the second (or west) line, (see diagrams, figs. 6 and 7.) The main-circuit wires of said second line are connected respectively with the posts *L* and *M*, so as to be closed through the connecting-spring *p*, whilst the magnets *F* of the instrument are placed in the local circuit connected with the relay and local battery of its own line. Hence, with this instrument the main circuit connected thereby is kept closed when its sounder-lever is at rest, (see diagram, fig. 6,) and when the main circuit is opened by the movement of said lever the local circuit of the second line is thereby also opened, (see diagram, fig. 7,) the adjustments being so made as that the local shall first be broken, and, in reverse, the main circuit be first closed by its movements.

In order to cut out at pleasure both the main circuit and second local from the instrument, I use an improved switch, constructed of a plate, *P*, figs. 4 and 5, of some non-conducting material, or otherwise properly insulated, provided with an arm, *Q*. This plate is pivoted centrally upon a pin, *V*, fig. 5, projecting through the base of the instrument, and encircled by a spring, which, by its tension, shall keep down the plate *P* firmly yet elastically. Beneath this plate are placed four independent metallic pins or points 1 1 and 2 2, (fig. 5, and dotted lines, fig. 4,) connected respectively in pairs, 1 and 1, 2 and 2, with the wires of the main circuit from the posts *L* and *M*, and of the local from the posts *H' K'*.

Upon the upper side of the plate *P* are placed transverse strips of metal *t t'*, provided at each end with metallic pins passing through the plate to come in line and contact, each, with one of the points 1 1 and 2 2 in the table below, the transverse strips *t t'* being so arranged as that when the plate *P* is placed in a right position, as shown in fig. 1, the pins 1 and 1 shall each be in contact with the two points projecting from one strip *t*, and the pins 2 and 2 with the two points from the other strip *t'* of the plate *P*, and a connection be thus formed across through said strips between each pair 1 1 and 2 2. If, however, the plate *P* be turned out of a right line upon its pivot, *V*, by means of its arm, *Q*, the points projecting from its strips will be each removed from the pins below, and all communication through the same be at once broken. The tension of the spring upon the pivot-pin *V*, insures proper contact between all the pins and points when they are brought into proper alignment.

The diagrams, figs. 6 and 7, representing east and west lines entering an office, with their connected instruments, illustrate my invention in the working of these two lines. In diagram, fig. 6, the lines are represented as idle and the instruments at rest. When the lines are thus quiet, the main circuits, east and west, are both kept constantly closed by the automatic operation of the keys *A A*.

The contact of the platina points in the keys renders the connection at all times sure and reliable, and the position of these points of contact and mode of securing the same under the pressure of the spring, render a displacement of the key, or a break from carelessness and inattention, almost impossible.

While the main circuits are thus closed, the magnets of the receiving-instruments, 10 and 20, of the apparatus, are kept constantly excited, so as to attract the armature-levers, (which, in each instrument, form part of a local circuit,) and retain them against insulated points, so that the local circuits all stand open when the lines are not working, and their batteries consequently gain, meantime, in strength and power; instead of being used up, as in the ordinary forms of telegraphic apparatus.

This feature of my invention is of very great advantage in fire-alarm telegraphs and in apparatus for private lines, which are the greater part of the time idle, and I contemplate the application thereof and of my instruments, constructed or arranged substantially as herein described, to such telegraphs.

With the lines at rest, and the local circuits all standing open, as represented, the repeating-sounders *G* rest open, and the main circuit consequently remains closed through the posts *L M* and connecting-spring *p* of each instrument, all as fully illustrated in the diagram, fig. 6.

If, now, with the apparatus at rest, as illustrated in diagram, fig. 6, the operator upon the line east writes, when he opens his key it will break the east line, releasing immediately the armatures of the east receiving-magnet 10 and relay 20, (as well as of the east sounder 11,) so that their springs shall bring them into contact with the anvils, to form a connection and close their local circuits, as illustrated in diagram, fig. 7.

It will be observed that an escape on the line, instead of decreasing the register or sounder-force, making it work hard, as with the ordinary relays, increases the sounder-force; that is, it causes the armature to be the more readily released by weakening the attraction thereon, thus making it work more quickly and easily. With ordinary instruments, the writing through an escape comes too heavy, from the fact that the instruments are operated by the close of the circuit, so that the effect of the escape is to weaken the force by which the armature is moved; whereas, with my apparatus, the circuit is opened by the operator in writing, and an escape, facilitating, as it will, this opening, will make the writing "lighter;" that is to say, the signals will come quicker and easier. The current on the line can vary until it becomes weaker than the springs of the armature-levers before it can interrupt the working of the instruments, thus avoiding the necessity of constant adjustment.

In diagram, fig. 7, the apparatus is illustrated working. The eastern operator having, by signal, opened the east circuit, the armatures of the receiving and relay-instruments 10 and 20 are released, thereby closing their local circuits, so that the magnets of the sounder 11 and repeating-instrument 12, becoming excited, will overcome the tension of their retaining-springs, and close their levers.

It will be observed that I thus cause the sounders to operate with a closed main circuit in the same manner as in the ordinary open-circuit systems, and that they are closed by the magnets instead of by a spring.

The closing of the sounder-lever G in the repeater, causing the insulated pin or screw thereof to bear upon the spring-plate p, connecting the posts L and M in the main circuit of the west line, will open the line at this point, repeating the signal west, whilst at the same time the local circuit of the west repeater is broken by the disconnection of the lever G from the post K, so that the west repeater will meanwhile remain quiet, and the possibility of a break and interruption of the east line from the west, while east is working, prevented.

When the main lines are cut off from the instruments, or the office closed for the day, the springs on the relays should be let down so as to allow the levers to rest on the insulated points, and keep their local circuits open, or the local circuits may be disconnected, and opened by means of a switch.

The improved switch P, figs. 4 and 5, serves to cut out the repeater whenever it may be desired.

Having thus fully described my invention, I do not claim broadly the operation of telegraphic signal and repeating-instruments by means of a closed main circuit, to be opened by a manipulation of the key or circuit-breaker; but

What I claim as my invention, and desire to secure by Letters Patent, is—

1. So combining the local circuit, influencing and operating a registering, repeating, or signal-instrument in an electro-magnetic telegraph system, with a receiving or relay-instrument on a main circuit in said system, as that said local circuit shall stand open when the main circuit is closed, and *vice versa*, all substantially in the manner and for the purpose herein set forth.

2. An electro-magnetic telegraphic relay or receiving-instrument, so constructed as that the contact of its armature-lever with a suitable connecting conducting-point to close a local circuit, shall be broken, and the local circuit thereby opened when the receiving-magnet becomes excited, all substantially in the manner and for the purpose herein set forth.

3. The combination and arrangement of the armature-lever of a telegraphic repeating-instrument with the wires of the local circuit, and a connecting and conducting-post in said circuit, so as that the local circuit shall be closed through said lever and post when the magnet attracting said lever is inactive, all substantially in the manner and for the purpose herein set forth.

4. So combining the connecting-device in a repeating-instrument whereby the main circuit is closed, with an insulated pin upon the armature-lever thereof, as that said main circuit shall be opened when the magnet of the instrument is excited; all substantially in the manner and for the purpose herein set forth.

5. The improved connecting and conducting-post M in my repeating-instrument, when constructed with a horizontal arm, s, carrying an adjusting-screw and connecting-pin, r, and combined with an elastic metallic strip, p, from a second conducting-post, L, to open and close an electrical circuit, all substantially in the manner and for the purpose herein set forth.

6. The telegraphic switch P, constructed of an insulated pivoted plate, provided with metallic strips, each so disposed thereon as that, by a proper alignment thereof, a connection may be formed thereby between any two detached pins or points beneath the plate communicating with the wires of electro-magnetic batteries, to be broken by turning the plate upon its pivot, so as to change the alignment, all substantially in the manner and for the purpose herein set forth.

7. My improved key or circuit-breaker, so constructed as that when at rest, the main circuit connected therewith shall be closed thereby through its lever, its base-plate, and an insulated anvil, substantially in the manner and for the purpose herein set forth.

The foregoing specification of my improvements in telegraphic apparatus signed by me, this fourth day of February, A. D. 1868.

W. G. BROWNSON.
